COOKER

Robert W. Thomas, Wichita, Kans., assignor to
William D. Devore and R. A. Devore

Filed Nov. 5, 1971, Ser. No. 196,254

Term of patent 14 years

Int. Cl. D7—02

U.S. Cl. D44—1 F

FIG. 1 is a top plan view of a cooker showing my new design;

FIG. 2 is a top perspective view;

FIG. 3 is an elevational view from the side opposite that seen in FIG. 2; and

FIG. 4 is a bottom plan view.

I claim:

The ornamental design for a cooker, substantially as shown and described.
